UNITED STATES PATENT OFFICE.

JOSEPH ROOP, OF FRANKFORT, INDIANA.

TIE-STRAP.

1,077,559.

Specification of Letters Patent.

Patented Nov. 4, 1913.

Application filed May 20, 1913. Serial No. 768,816.

To all whom it may concern:

Be it known that I, JOSEPH ROOP, a citizen of the United States, residing at Frankfort, in the county of Clinton, State of Indiana, have invented certain new and useful Improvements in Tie-Straps; and I do hereby declare the following to be a full, clear, and exact description of the invention, such as will enable others skilled in the art to which 10 it appertains to make and use the same.

This invention relates to tie straps and has for an object to provide an extremely simple and inexpensive device of this character which may be easily and quickly applied and 15 when applied will be held against displacement or working loose.

A further object is to provide a tie strap having hooked ends one of which is adapted to engage with the outer edge of the flange 20 of the rail or the like to which the tie strap is applied, and the other of which is designed to receive a wedge-plate which bears against the web of the rail and when driven home tightly binds the tie strap in place.

With the above objects in view the invention consists of certain novel details of construction and combination of parts herein-after fully described and claimed, it being understood that various modifications may 30 be made in the minor details of construction within the scope of the appended claims.

In the accompanying drawing illustrating this invention:—Figure 1 is a cross sectional view showing the tie strap in use upon two 35 rails. Fig. 2 is a plan view of the strap. Fig. 3 is a plan view of a modified form of the strap. Fig. 4 is a cross sectional view showing the tie strap modified for application to an I-beam.

Referring now to the drawing in which like characters of reference designate similar parts, 10 designates the strap, the ends of the strap being curved inwardly and backwardly upon the same side of the strap to produce 45 lips 11 and 12, one of the lips being formed in the edge with openings 13 to receive the heads of bolts 14. A wedge shaped plate 15 is received between the body of the strap and the lip 12 and is formed with openings 50 16 to receive the bolts 14. As shown in Fig. 3, the bolts for securing the wedge plate in position may be dispensed with and a cotter

pin 17 may be substituted, in either instance, such bolts or the cotter pin when applied serving to positively prevent backing out of 55 the wedge plate from its operative position.

As shown in Fig. 1, the strap is applied to railway rails 18, the lip 11 engaging the outer edge of the base flange of one of the rails while the wedge-plate bears upon the 60 top face of the base flange of the other rail and engages with its edge the web of the rail whereby the tie strap is drawn tightly into position and holds both rails against outward spreading. The usual clamp strap 65 19 is shown, the ends of this strap bearing upon the top face of the inner sides of the base flanges of both rails, while bolts 20 are passed through the clamp strap and through the tie strap to securely hold the 70 parts together.

In Fig. 4 there is shown a modified form of the tie strap, the same being designed to engage with an I-beam 21 and form means for securing the same to a support. In this 75 modification the body of the strap is offset centrally as shown at 22 and receives an attaching bolt 23, the lip 11 engaging over one edge of the beam flange as above described while the lip 12 is positioned above the other 80 edge of the base flange and holds the wedge plate 15 in position against the web of the beam, the securing bolts 14 positively holding the wedge plate in place.

From the above description it will be seen 85 that I have provided a novel tie strap having a lip and a wedge plate that coacts therewith in tightly holding the tie strap in operative position against accidental displacement.

What is claimed, is:—

1. A tie strap having the ends bent back upon one side of the body of the strap and producing hook-like lips, a wedge plate carried in the inclosure of one of said lips, recesses in the wedge plate confining lip, and 95 bolts passed through said wedge plate and the body of said strap and having the heads disposed within said recesses.

2. The combination with a member having a web and a base flange, of a strap having 100 the ends bent back upon one side of the body of the strap to produce hook-like lips, one of said lips receiving within its inclosure and engaging with one edge of said flange,

a wedge plate within the inclosure of the other of said lips and bearing with its edge upon the member web and serving to bind said strap tightly in position upon said base flange, and bolts passed through said wedge plate and its confining lip for preventing displacement of said wedge plate.

In testimony whereof, I affix my signature, in the presence of two witnesses.

JOSEPH ROOP.
